UNITED STATES PATENT OFFICE

122,732

DESIGN FOR A WRINGER FINGER GUARD

Thomas H. Buchanan, Steubenville, Ohio

Application February 6, 1940, Serial No. 90,073

Term of patent 7 years

To all whom it may concern:

Be it known that I, Thomas H. Buchanan, a citizen of the United States, residing at Steubenville, in the county of Jefferson and State of Ohio, have invented a new, original, and ornamental Design for a Wringer Finger Guard, of which the following is a specification, reference being had to the accompanying drawing, forming part thereof.

and

I claim:

The ornamental design for a wringer finger guard, as shown.

THOMAS H. BUCHANAN.
